DISPLAY RACK

Frank W. Bofenkamp and James Sabino,
Albuquerque, N. Mex.

Application July 18, 1940, Serial No. 346,230

2 Claims. (Cl. 211—181)

This invention relates to new and useful improvements in display racks and it is an improvement on the subject matter of our co-pending application Serial No. 294,020, filed September 8, 1939.

The principal object of the present invention is to provide a display rack for use in display refrigerators which will serve to support meat and various other commodities in an attractive manner and wherein the rack is so constructed as to permit ornamentation to be placed thereon to pleasingly add to the display of commodities.

Various other important objects and advantages of this invention will become apparent to the reader of the following description.

In the drawings:

Figure 1 represents a vertical sectional view through the upper portion of a refrigerator showing the rack disclosed in commodity supporting position.

Figure 2 is a fragmentary top plan view of the rack.

Figure 3 is a perspective of one of the sections of the rack with the majority of the commodity supporting rods removed.

Figure 4 is an enlarged fragmentary detailed sectional view taken substantially on the line 4—4 of Figure 2 and showing artificial parsley or some other ornamenting substance in dotted lines.

Referring to the drawings wherein like numerals designate like parts, it can be seen that the rack can be made up of a plurality of sections of such construction as that shown in Figure 3. Each section will consist of an angularly constructed frame including a vertical back member *a*, a base member *b* and an inclined member *c* connecting the members *a* and *b*, these frames 5 are connected at their upper corners by horizontal rails 6 and at their lower rear corners by rails 7. The forward corners of the frames 5 are connected by a rail 8. Additional rails 9 and 10 are provided at equal distant intervals with downward offsets 11, and excepting for these offsets 11 supporting rods 12 are laid across the rails 8, 9, 10 and 6 and suitably secured thereto, as by welding.

Each of the frame members *c* has a pair of hook members 13 extending therefrom and these hook members are offset with respect to corresponding hook members on complementary rack sections

so that they can interlap as shown in Figure 2.

On the market at present are certain artificial forms of decorative means and one in particular is an artificial parsley which has leaves 14 extending from a relatively rigid elongated member 15. The rigid members 15 are cut off at the proper length so that they can extend across the rack in parallel relation to the supporting rods 12 and seated in the offset 11, with the leaves 14 extending upwardly to substantially frame commodities placed on the rods 12 or on trays or plates supported by the said rods 12.

Furthermore, it can be seen that strips of this artificial parsley can be placed in the interlapping hooks 13, also as suggested in Figure 4 and thus a multiple sectioned rack will to all outward appearance resemble a single one-piece support for the display commodities.

Obviously, the fundamental purpose for the rack is to permit a thorough circulation of cold air over and below the supported commodities without the rack presenting a more or less objectionable appearance to customers.

As shown in Figure 1, the rack sits upon a stepped shelf 16 in the refrigerator 17 and can be readily removed.

While the foregoing specification sets forth the invention in specific terms, it is to be understood that numerous changes in the shape, size and material may be resorted to without departing from the spirit and scope of the invention as claimed hereinafter.

Having described the invention, what is claimed as new is:

35 1. A display rack comprising a frame having hook members at the ends thereof for supporting ornamental display means, a cross member bridging the frame and longitudinally extending members bridging the ends of the frame and having downwardly disposed ornamental element receiving offsets therein.

40 2. A display rack comprising a plurality of rack sections provided with interlapping hook members at adjacent ends thereof and an ornamental member of elongated shape disposed into said interlapping hooks to fill the space between the rack sections and connect said sections together.

FRANK W. BOFENKAMP.
JAMES SABINO.
